US00D920317S

(12) **United States Design Patent** (10) **Patent No.:** **US D920,317 S**
(45) **Date of Patent:** **** May 25, 2021**

(54) **CASE FOR ELECTRONIC COMMUNICATIONS DEVICE OR THE LIKE**

(71) Applicant: **Apple Inc.**, Cupertino, CA (US)

(72) Inventors: **Jody Akana**, San Francisco, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Jeremy Bataillou**, San Francisco, CA (US); **Daniel J. Coster**, San Francisco, CA (US); **Daniele De Iuliis**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Duncan Robert Kerr**, San Francisco, CA (US); **Matthew Dean Rohrbach**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Christopher J. Stringer**, Woodside, CA (US); **Eugene Antony Whang**, San Francisco, CA (US); **Rico Zörkendörfer**, San Francisco, CA (US)

(73) Assignee: **Apple Inc.**, Cupertino, CA (US)

(**) Term: **15 Years**

(21) Appl. No.: **29/607,252**

(22) Filed: **Jun. 12, 2017**

Related U.S. Application Data

(63) Continuation of application No. 29/538,665, filed on Sep. 4, 2015, now Pat. No. Des. 789,346.

(57) **CLAIM**

The ornamental design for a case for electronic communications device or the like, as shown and described.

DESCRIPTION

FIG. 1 is a bottom rear perspective view of a case for electronic communications device or the like showing the claimed design;

FIG. 2 is a bottom view thereof;

FIG. 3 is a top view thereof;

(Continued)

FIG. 4 is a left side view thereof;
 FIG. 5 is a right side view thereof; and,
 FIG. 6 is a rear view thereof.
 The dashed broken lines in the figures show portions of the case that form no part of the claimed design.
 The dot-dash broken line in FIGS. 1 and 4-6 represent a boundary of the claimed design. The dashed and dot-dash broken lines form no part of the claimed design.

1 Claim, 4 Drawing Sheets
